Patented Mar. 18, 1919.

UNITED STATES PATENT OFFICE.

HERMON L. VAN VALKENBURG, OF MILWAUKEE, WISCONSIN, ASSIGNOR TO INDUSTRIAL CONTROLLER COMPANY, OF MILWAUKEE, WISCONSIN, A CORPORATION OF WISCONSIN.

MAGNETICALLY-CONTROLLED SWITCH.

1,297,979.

Specification of Letters Patent. Patented Mar. 18, 1919.

Application filed April 7, 1916. Serial No. 89,684.

To all whom it may concern:

Be it known that I, HERMON L. VAN VALKENBURG, a citizen of the United States, residing at Milwaukee, in the county of 5 Waukesha and State of Wisconsin, have invented a certain new and useful Improvement in Magnetically-Controlled Switches, of which the following is a specification.

My invention relates to magnetically controlled switches intended primarily to be used in connection with motor starters. The general object of the invention is to provide electromagnetic means for automatically operating the switch element when the current 10 reaches a preordained critical value. One of the specific objects is to provide a construction by which, when the current falls below a given value and the switch element moves, the holding action of the device will be augmented. In the design illustrated, there is a main operating and also a lockout coil, and when the lockout coil lets go, its plunger moves into the field of influence of the operating coil which supplements the action of 15 the plunger of the operating coil. Another object is to provide means for regulating the action of the device.

I obtain my objects by the mechanism illustrated in the accompanying drawings, 20 in which—

Figure 1 is a central vertical section of a switch embodying a component part of the invention. In this figure the elements are shown in the position which they will assume when the circuit is dead.

Fig. 2 is similar to Fig. 1, and shows in full lines the positions which the parts will assume when energized by a current of comparatively high value. The dotted lines indicate the position which the parts will assume when the energizing current falls below the critical value.

Fig. 3 is a top plan of the parts shown in Figs. 1 and 2.

Fig. 4 is a diagram illustrating the principle of operation, of one type of controller employing the switch of Figs. 1, 2 and 3.

In the accompanying drawings, which illustrate certain forms which my invention 50 may assume, similar reference characters denote similar parts throughout the several views.

Referring first to Figs. 1, 2 and 3: A panel

1 of slate or other insulating material supports two contacts 2, 3, these representing 55 the two terminals of a supply circuit. These contacts are secured to the panel in any suitable manner and are energized through the respective conductors 4 and 5 which lead in preferably from the back of the panel as 60 best shown in Fig. 3. A movable contactor 6, which in the construction shown, assumes the form of a circular metallic disk, is rigidly secured by lock nuts 7 or other suitable means to the upper end of a rod 8. 65 The parts are so arranged that when the rod raises the contactor, said contactor will bridge the contacts 2 and 3.

Rod 8 is here shown to be arranged vertically and to be vertically movable, being 70 guided at the upper end by a bushing 9 carried by the upper horizontal arm of a frame 10, which, when viewed in vertical section, is U-shaped, and attached at the back to the panel by means of a bolt 12 or other appropriate fastening means. This frame is of iron or other material of magnetic permeability and supports an operating or main coil or winding 13 between its upper and lower branches. By preference, this 75 coil is lined with tubing 14 of brass or a suitable substitute,—this tubing is shown to be outwardly flanged at the top and bottom with the flanges inserted between the horizontal arms of the frame 10 and the end 85 disks 15, 15 of said operating coil. A second tubing 17, preferably of brass, is fitted within the tubing 14 and extends down into the second magnet frame 20, which is similar to the first frame 10, except that it is 90 shorter. It is fastened to the panel by a stud 22 or other suitable fastening device. The coil 21, which I shall refer to as the “holding coil” or “lockout coil” has terminal disks 23 of insulating material. Coil 21 is 95 lined by a tube 24 similar to the tube 14 of the operating coil 13. A core 27 fits slid- 100 ingly within the inner guide tube 17 and is rigidly fastened to the lower end of rod 8. Normally said core, which may be termed 105 the “holding core” seats upon a stop which here assumes the form of a brass collar 27a. A screw 28 of iron or other metal having high permeability screws into the lower arm of frame 20 and is held locked in proper po- 110sition by a nut 20. By adjusting said screw,

the air gap between it and the holding core 27 may be varied, thus regulating the point at which the holding coil will release.

Above the holding core 27 is an element 5 32, which may be designated as the "operating core." This fits slidably within the guide tube 17 and by preference is separated from the holding core by a washer 33 of brass or other material for preventing the 10 two cores from sticking together. By preference, a brass washer 34 is provided at the upper end of the operating core 32, to prevent sticking to the part 9 of the frame due to residual magnetism. Said operating core 15 is longitudinally chambered from the top to a point near the bottom and at the bottom said core is apertured to accommodate the rod 8 and permit independent vertical movement of the rod and operating core. A helical compression spring 36 encircles the rod 8 and at the lower end seats upon the bottom of the chamber formed within the operating core. At the upper end said spring 20 engages the under side of a collar 38, which is rigidly fastened to the rod.

Now describing the operation of the unit shown in Figs. 1, 2 and 3:

When the coils are unenergized, the two cores 27 and 32 remain down and the switch 30 stands open as shown in Fig. 1. If, now, a current of comparatively high value passes through the coils, the holding coil 21 will hold down its core 27, but the operating coil 13 will raise its core 32 and compress 35 spring 36 as shown in Fig. 2. Under these conditions the switch remains open. If the energizing current thereafter drops below a certain predetermined point, the holding coil will be weakened to such an extent that 40 it will be no longer able to hold down its core in opposition to the force of the spring, and the holding core and the contactor 6 attached thereto will rise. As the holding core rises, it comes into the magnetic field 45 of the operating coil, which exerts a strong upward pull upon it, and firmly closes the switch. In practice the parts are so designed that when the switch is closed the spring will be compressed to only a slight 50 extent, if at all, while the operating coil will exert a strong upward pull on the contactor. The result is that the device is very positive in its action and the contactor is held in firm and close contact with the terminals 2, 3.

Referring now to the diagram of Fig. 4, in which the above described switching unit is employed:

R, R¹ and R² represent three sections of 60 starting resistance, which in the present instance are in series with the armature M of the motor. The conductors S and S¹ represent the opposite sides of the supply circuit and these conductors are controlled by 65 manually operated switches s and s¹ respec-

tively. The field F of the motor is here shown as a shunt field, energized by the conductors f and f¹ connected in the manner hereinafter described.

A, B and C represent three units as detailed in Figs. 1, 2 and 3. Tracing out the circuits, the switch s is connected through conductors 50, 51 and 52 to the resistance R. At the other end, said resistance is connected by a conductor 53 to one of the terminal contacts 54. A conductor 55 leads from contact 54 to the operating coil a of the first switch A. Coil a is connected in series with the coil a¹, these coils corresponding respectively to the operating coil 13 and the holding coil 21, shown in Figs. 1 and 2. These coils operate the contactor 56 in the manner in which the coils 13 and 21 operate the contactor 6 of Figs. 1 and 2. A conductor 57 connects the holding coil a¹, to one end of the resistance R¹. The other end of this resistance is connected to the resistance R² and also to the conductor 58 which leads to the coil c¹ of the switch C. Said coil corresponds to the holding coil 21 of the unit shown in Figs. 1, 2 and 3. The other end of the coil c¹ is connected by a conductor 59 to the stationary contact 60, which forms part of the switch unit B. The stationary contact 61 forms a companion terminal to the contact 60 and is in position to be connected therewith by the contactor 62 of switch unit B. Contact 61 is connected through a conductor 62 to the stationary contact 63 which forms a companion terminal to the stationary contact 54 of the switch unit A. A conductor 64 leads from conductor 62 to the operating coil b of the switch unit B; said coil is connected in series to the holding coil b¹ of switch unit B. The other end of the holding coil b¹ is connected by a conductor 65 to the conductor 50. The resistance R² is connected by a conductor 66 to the stationary contact 67 which forms one of the terminals of the switch unit C. This contact is in position to be engaged by the contactor 68 of the switch unit C. A contact 69 forms a companion terminal to the contact 67 and is connected to the conductor 51 by the conductor 70. Contact 67 is connected by the conductor 71 to one terminal of the armature M of the motor; the other terminal of the armature is connected by a conductor 72 to the switch s¹. An auxiliary contact 73 is provided in the unit B in position to be engaged by the contactor 62. This auxiliary contact is connected by a conductor 74 to one end of the operating coil c of the switch unit C. The other end of this coil is connected by a conductor 75 directly to the conductor 72. A resistance 76 is connected at one end to conductor 74 and at the other end to the contactor 68. Thus when contactor 68 is closed, the operating coil is in a shunt circuit around the motor armature M.

shunt circuit is protected by suitable resistance. The field conductor f , previously mentioned, is connected to the conductor 72 and the field conductor f^1 is connected to the conductor 65.

When the parts are connected as shown in Fig. 4, the operation is as follows:

When the operator wishes to start the motor he moves the hand switches s , s^1 to closed position. Prior to closing these hand switches, the switch units A, B and C, being totally unenergized, will stand in open position shown in the diagram; but as soon as switches s , s^1 are closed, full initial starting current will flow through the conductors 50, 51 and 52 to the resistance R, thence through the conductors 53 and 55, through the series coils a , a^1 , thence through the conductor 57 to the resistances R^1 and R^2 , thence through the conductors 66 and 71, through the armature M, out through the conductor 72 and switch s^1 to the opposite supply conductor S^1 . As the motor is initially standing still it will at first be creating no counterelectromotive force and hence the current flowing through the controlling apparatus will be at a maximum so far as permitted by the resistances which are in circuit. With the current thus at a maximum value, the holding coil a^1 will be able to hold the contactor 56 down in open position notwithstanding the fact that the operating coil a will, in accordance with the principle illustrated in Figs. 1 and 2, raise its inclosed core and compress its inclosed spring. But as the motor commences to speed up it creates a counterelectromotive force until the current falls below the critical value and weakens the electromagnetic effect of the holding coil a^1 to such an extent that the inclosed spring in the operating coil a overcomes the holding effect of the coil a^1 and brings the contactor 56 to closed position. This short-circuits the resistance R and the current will flow from switch s through the conductors 50 and 65, through the coils b^1 and b of the switch unit B; thence it flows through the conductor 64 and contactor 62 to the contact 63, whence it is led into the contactor 56, which is now in closed position, to the stationary contact 54; thence through the conductor 55 and coils a and a^1 and conductor 57 to the resistances R^1 and R^2 and out through the armature. The current continues to flow along this path until the motor, in increasing its speed, reduces the current to a value below the point where the holding coil b^1 will have sufficient electromagnetic influence to maintain the contactor 62 in open position. Thereupon, said contactor rises and bridges the contacts 61, 73 and 60. This cuts out the resistance R, for the current will now flow through the conductors 50 and 65 and coils b^1 and b^2 through the contactor 62 to the contact 60, whence it will flow through the conductor 59 and coil

c^1 to the conductor 58, thence through the resistance R^2 and thence out through the motor armature to the opposite side of the line. When this status is reached, the operating coil c will be energized through the conductor 74 which is connected by the conductor 75 directly to the opposite side of the line instead of being connected through the motor. When the speed of the motor approaches maximum and the current in the coil c^1 falls below the critical value, the contactor 68 moves to closed position. This short circuits all of the starting resistance and also puts the coil c in a shunt circuit, consisting of the resistance 76, coil c and conductor 75, thus holding the last switch closed regardless of the fluctuations in the armature circuit; in fact the current in the armature circuit may even be momentarily reversed without affecting said switch.

Having thus described my invention, what I claim as new and desire to secure by Letters Patent, is:

1. An electro-magnetically operated switch having a movable switch element, two magnetic plungers mechanically connected thereto, and a separate coil for each plunger adapted, when energized, to pull in opposite directions, the plunger of one coil, when the other predominates, moving away from its own coil and toward and into the magnetic field of the other coil.

2. An electro-magnetically operated switch having a movable switch element, two magnetic plungers mechanically connected thereto, a separate coil for each plunger adapted, when energized, to pull in opposite directions, the coil being in series and one being stronger than the other whereby it may, under certain conditions, predominate over the weaker coil, the plunger of the weaker coil, when the stronger predominates, moving away from its own coil and toward and into the magnetic field of the stronger coil.

3. An electro-magnetically controlled switch having two windings, each having a plunger movable relatively to it for cooperatively controlling the switch element, the windings tending, when energized, to influence the plungers oppositely, and one of the plungers being normally remote from the field of the other winding but movable thereinto for producing a cumulative effect upon the switch element.

4. An electro-magnetically controlled switch having a movable switch element and two plungers for actuating it, each plunger having a separate winding of its own, the plungers and windings being relatively movable, and the two windings, when energized, producing opposite effects upon their plungers, one winding being stronger than the other and the plunger of the weaker winding being normally practically out of the field of the stronger winding but

moving thereinto to produce a cumulative force upon the switch element when the weaker winding has been deenergized to such an extent as to be unable to hold back 5 its plunger.

5. In combination, a switch element, a spring for actuating said switch element, a plunger for straining said spring, a winding for operating said plunger, a holding plunger for preventing the actuation of the switch element notwithstanding the force of the spring, and a holding winding co-operating with said holding plunger, said spring, when said holding winding becomes deenergized to such an extent that it cannot overcome the force of the spring, moving the plunger of the holding winding into the field of the first mentioned winding. 10 15

6. A magnetically controlled switch having a main coil, a lockout coil, a switch element, a spring, a plunger in the main coil adapted when its coil is energized to strain said spring to thus urge the switch element forward, a plunger in the lockout coil adapted when its coil is energized to urge the switch element backward, and mechanical means for regulating the maximum effort that the lockout coil can exert on its plunger for any given value of energization 25 30 of the lockout coil.

7. A magnetically controlled switch having a main coil, a lockout coil, a switch element, a spring, a plunger in the main coil adapted, when its coil is energized, to strain said spring to thus urge the switch element forward, a plunger in the lockout coil adapted, when its coil is energized, to urge the switch element backward, and an adjustable stop fixed with reference to the lockout coil 40 for regulating the distance to which the plunger of the lockout coil may enter, whereby to regulate the maximum effort that the lockout coil can exert on its plunger for any given value of energization. 45

8. A magnetically controlled switch having a main coil, a lockout coil, a switch element, a spring, a plunger in the main coil, adapted when its coil is energized to strain said spring to thus urge the switch element forward, and a core in the lockout coil 50 adapted, when its coil is energized, to urge the switch element backward, the two coils being in series and being so designed that at any given value of current the pull which the main coil exerts upon its plunger is greater than the pull which the lockout coil exerts upon its plunger. 55

9. A magnetically controlled switch having a main coil, a lockout coil, a switch element, a spring, a plunger in the main coil adapted, when its coil is energized to strain said spring to thus urge the switch element forward, and a plunger in the lockout coil adapted, when its coil is energized, to urge 60 65 the switch element backward, the two coils

being in series, and so wound that their magnetic fluxes oppose each other, said coils being so designed that the main coil exerts a greater pull upon its plunger than the lockout coil does upon its plunger for any given value of current, and the coils being so close together that when the lockout coil releases its plunger it enters the magnetic field of the main coil and thus adds to the forward pressure upon the switch element. 70 75

10. In combination, a normally open switch, a spring for closing said switch, a movable core, an operating coil, which, when energized, moves said core to a position to strain said spring and thereby urge the switch toward closed position, a holding coil having a core mechanically connected to said switch, said holding coil when energized above a predetermined point holding its core in position to hold the switch open in opposition to the force of the spring, said holding coil when energized below said predetermined point exerting insufficient influence upon its core to resist the force of the spring, and mechanical means for regulating the maximum amount of pull which the holding coil can exert upon its core with any given amount of energization of said holding coil. 80 85 90

11. In combination, a normally open switch, a spring for closing said switch, a movable core, an operating coil, which, when energized, moves said core to a position to strain said spring and thereby urge the switch toward closed position, a holding coil 95 having a movable core mechanically connected to said switch, said holding coil when energized above a predetermined point holding its core in position to hold the switch open in opposition to the force of the spring, 100 said holding coil when energized below said predetermined point exerting insufficient influence upon its core to resist the force of the spring, and a stop for limiting the extent 105 to which the holding core can enter into said holding coil. 110

12. In combination, a normally open switch, a spring for closing said switch, a movable core, an operating coil, which, when energized, moves said core to a position to 115 strain said spring and thereby urge the switch toward closed position, a holding coil having a movable core mechanically connected to said switch, said holding coil when energized above a predetermined point holding its core in position to hold the switch open in opposition to the force of the spring, 120 said holding coil when energized below said predetermined point exerting insufficient influence upon its core to resist the force of the spring, a stop for limiting the extent to which the holding core can enter the holding coil and a stationary core at one end of the holding coil, said stationary core being adjustable toward and from the movable hold- 125 130

ing core to thereby vary the air gap between them and regulate the conditions under which the movable holding core will be released.

- 5 13. In a switch unit, a contactor, an operating coil having a core for urging said contactor toward closed position, a holding coil having a movable core connected to said contactor for holding said contactor open
 10 when said holding coil is energized above a predetermined point and for releasing said holding core when said holding coil is energized below said predetermined point, said coils being separate but arranged endwise
 15 whereby said holding core moves into the field of the operating coil when released by said holding coil, and is urged by said operating coil in a direction to close the contactor.
 20 14. In a switch unit, a contactor, a spring for urging it to closed position, an operating coil having a movable core for straining said spring, a holding coil having a movable core mechanically connected to said contactor for holding the contactor in open position in opposition to the force of the spring when the holding coil is energized above a certain degree and for releasing said holding core when said holding coil is energized
 25 below said degree, said coils being separate
 30

but arranged endwise, and the holding core when released moving into the field of the operating coil whereby the operating coil thereupon urges the contactor toward closed position.

35

15. In a switch unit, a contactor, an operating coil having a core for urging said contactor toward closed position, a separate holding coil in series with the operating coil and having a movable core connected to said contactor for holding said contactor open when said holding coil is energized above a predetermined point and for releasing said holding core when said holding coil is energized below said predetermined point, said coils being arranged endwise whereby said holding core moves into the field of the operating coil when released by said holding coil, the holding coil being mechanically limited in its movement away from said operating coil, said holding coil also having a stationary core at one end of the holding core, and the stationary core being adjustable toward and from the holding core to vary the air gap between them and thus vary the releasing point of the holding coil.

40

45

In witness whereof I have hereunto subscribed my name.

HERMON L. VAN VALKENBURG.
